UNITED STATES PATENT OFFICE

2,193,343

VARIOMETER

John P. Putnam, Boston, Mass., assignor to The
Reece Button-Hole Machine Company, Boston,
Mass., a corporation of Maine

Original application July 5, 1935, Serial No. 29,866.
Divided and this application February 5, 1936,
Serial No. 62,457

2 Claims. (Cl. 171—242)

This invention relates to variometers especially adapted, although not limited, to tuning units for radio receivers of the "all-wave" type.

One object of the invention is to provide means 5 for augmenting the rate of progressive increase of the figure of merit of a variometer, i. e., the ratio of the total inductive reactance thereof to its total resistance, over the greater part of the 10 variometer inductance-range, i. e., the ratio of its maximum to its minimum inductance, and to augment such ratio, which is a maximum at the upper end of said range. This object is effected by providing one of the variometer windings with 15 a core of paramagnetic material such as finely divided iron held together with a binder and compressed into shape under extremely high pressure, said core constituting an open magnetic circuit having constant reluctance for all positions of the rotor winding.

Another object is to provide means for eliminating the noises produced in a radio receiver embodying my improved variometer due to electrical disturbances that result from the relative movement of the variometer rotor in its 20 supporting frame. This object is accomplished by mounting the rotor support member for rotation in an opening formed in the metallic support member by means of an insulating disc.

Various other objects and advantages of my 25 invention will appear in the detailed description of the embodiment thereof illustrated in the accompanying drawing in which

Figure 1 is a vertical section of a variometer embodying my invention.

Fig. 2 is a perspective view of one portion of the variometer rotor and its support member.

Fig. 3 is a perspective view of the variometer stator and the support member therefor.

Fig. 4 is a perspective view of the other portion 30 of the variometer rotor and its support member.

In the exemplification of the invention shown in the drawing, the portion 10 of the rotor frame or support member is provided with a spherical interior surface 11 in which is mounted one portion 35 of the rotor winding 12. The complementary portion 13 of said support member also is provided with a spherical interior surface 14 in which is disposed the other portion 15 of said rotor winding. The outer faces of the support

members 10, 13, are provided with registering circular apertures as indicated at 16. The stator windings 17, which co-operate with the rotor windings 12, 15, are mounted on the stator support member 18 which has a spherical exterior 40 surface. By means of the gudgeons 19, which are

disposed in the bearings formed by the complementary grooves 20, 21, in the support members 10, 13, respectively, the stator support is disposed in its proper position with respect to the rotor support and is held in such position when said members are secured together by screws (not shown) which pass through the registering holes 22, passing through the same at the corners thereof. The pin 23 rigidly secured to one of said gudgeons and held stationary in any suitable manner may constitute one of the terminals for connecting the variometer windings in circuit. The stator windings 17 and the rotor windings 12, 15, may be connected in series 45 or in parallel.

Enclosed within the central bore of the stator support 18 and held in position by the bushing 24 is a core 25 of paramagnetic material preferably formed by mixing finely divided iron with a binder and compressing the same into the desired shape under extremely high pressure, such cores being well-known articles of commerce and requiring no further description.

The rotor support may be mounted for rotation with respect to the stator support and the winding carried thereby in any suitable manner. In the present instance, it is shown as mounted in a metallic frame member 26 having a circular opening and the particular means employed for mounting the same in said opening is an insulating disc 27 formed of two semi-circular portions integral, respectively, with the parts 10, 13, of the rotor frame. This disc, in the particular embodiment of the invention shown in the drawing, has its bearing in the ball-cage 28 which projects into the circular opening aforesaid in the plate 26, the flange 29 on said cage holding the same in position. The metal disc 30 secured by screws, one of which is shown at 31, to the two-part insulating disc 27 carries the ball-cup 32 which projects into a cavity formed in the wall of the metallic ball-cage and co-operates with the periphery thereof to make a raceway for the anti-friction balls 33. The dial knob 34 is suitably secured to the stud 35 integral with the disc 30 which, as shown, is of smaller diameter than the inside diameter of the ball-cage and does not make rubbing contact therewith.

By mounting the variometer rotor support member for rotation in the metallic frame member 26 by means of said insulating discs, I eliminate the grinding noises that would be produced by a radio receiver embodying my variometer if said discs were metallic, such noises being caused by electrical disturbances due to the relative 50 55

movement of two contacting, conducting members only one of which is grounded.

By providing the variometer with a core having greater permeability than air, the magnetic field

- 5 is concentrated and leakage reduced, thus insuring a greater flux linkage between the coils. Another result obtained by using a magnetic core is that the "figure of merit" of the variometer, that is, the ratio of the total inductive reactance, 10 thereof to its total resistance, known as the "Q" of the variometer, is increased over the greater part of the variometer inductance-range or the ratio of its maximum to its minimum inductance. I have ascertained that the use of such core in 15 a variometer is practically without effect on the "Q" thereof at and near the lower end of its inductive range where the coils are in or near the position of maximum opposition and minimum inductance.
- 20 The minimum inductance of a variometer is equal to the sum of the self inductances of the rotor and stator coils minus twice the mutual inductance thereof. As the rotor is turned toward the position of maximum assistance and maximum inductance, such maximum inductance being equal to the sum of the self inductances of the rotor and stator coils plus twice the mutual inductance thereof, the "Q" of the variometer is progressively increased and is a maximum at 25 the upper end of the inductance range.

I have ascertained experimentally that the use of said core results in a marked increase in the variometer inductance range, i. e., the ratio of the maximum inductance of the variometer to the minimum inductance therefor.

In some of the tuning elements of the kind described in my application Serial No. 29,866, filed July 5, 1935, which has matured into Patent Number 2,066,945, dated January 5, 1937, of which 35 this application is a division, the inductance range of the variometer that forms the subject matter of the present application is 10:1 such ratio being specified herein merely by way of example and not as a limitation, and this relatively high 40 inductance range is an important factor in the elimination of the large number of tuning elements heretofore found necessary in each tuning unit of an all-wave radio receiver and the complex multi-contact switching member required for

selecting the same when passing from one frequency band to another. At 36 there is indicated a spiral hair spring disposed in the complementary semi-circular slots 37 formed, respectively, in the two parts 10 and 13 of the rotor support member. One end of said spring is connected electrically and mechanically to one of the stator gudgeons and the other end to the rotor support member. The two portions of the stator winding are connected electrically to the 10 gudgeons 19 and by means of said hair spring the rotor and stator windings are conductively connected. It will be understood of course that any other suitable means may be employed for connecting the variometer windings to each other, either in series or in parallel and to the circuit in which the variometer is used.

The ball-cage 28, in addition to its usual function, serves as a shield to screen the variometer from electrical forces that otherwise would pass 20 through the circular opening in the metallic frame member 26 within which the insulating disc 27 is disposed.

Having thus disclosed as illustrative embodiment of my invention without however limiting 25 the same thereto, what I claim and desire to secure by Letters Patent is:

1. A variometer having a rotor and a stator comprising windings, support members for said windings, a metallic frame member having a circular opening, and means for mounting the support member of the rotor windings for rotation in said frame member, said means comprising a disc of insulating material secured to said support member of the rotor windings and disposed in 35 said circular opening.

2. A variometer having a rotor and a stator comprising windings, support members for said windings, a metallic frame member having a circular opening, and means for mounting the support member of the rotor windings for rotation in said frame member, said means comprising a disc of insulating material secured to said support member of the rotor windings and disposed in 40 said circular opening, and a metallic shielding member arranged adjacent to said circular opening.

JOHN P. PUTNAM.
